(57) **CLAIM**

The ornamental design for a novelty base, as shown and described.

DESCRIPTION

FIG. 1 is a front perspective view of our novelty base; FIG. 2 is a front elevation view thereof; FIG. 3 is a rear elevation view thereof; FIG. 4 is a top plan view thereof; FIG. 5 is a bottom plan view thereof; FIG. 6 is a right side elevation view thereof; and, FIG. 7 is a left side elevation view thereof. The broken lines form portions of the novelty base that do not form part of the claimed design.
